Primary Examiner — Janice Patyk

(57) **CLAIM**

The ornamental design for a storage can for oil, as shown and described.

DESCRIPTION

Fig. 1.1 is a front view of the claimed storage can for oil, showing the new design;

Fig. 1.2 is a left view of the claimed design of Figure 1;

Fig. 1.3 is a right view of the claimed design of Figure 1;

Fig. 1.4 is a back view of the claimed design of Figure 1;

Fig. 1.5 is a top view of the claimed design of Figure 1;

Fig. 1.6 is a bottom view of the claimed design of Figure 1;

Fig. 1.7 is a perspective view of the claimed design of Figure 1;

Fig. 1.8 is another perspective view of the claimed design of Figure 1.

The broken lines in the figures illustrate portions of the storage can for oil that form no part of the claimed design.
